CLAIM

The ornamental design for a bicycle as shown and described.

DESCRIPTION

6. Bicycle

6.1 is a left side elevation view of a Bicycle embodying my new design;

6.2 is a top, front and right side perspective view thereof, and

6.3 is a top, rear and left side perspective view thereof. The broken line showing of various portions of a bicycle are provided for the purposes of illustrating environmental structure and form no part of the claimed design.
